ROTARY DRUM LAUNDRY MACHINE

Mike Kachuck, San Rafael, Calif.

Application May 28, 1951, Serial No. 228,660.

1 Claim. (Cl. 68—140)

1 The present invention relates to laundry machines, and more particularly to machines of the type having an open ended horizontally disposed rotatable drum with an open end through which laundry is introduced and withdrawn.

The object of the invention is to provide a new and novel arrangement, whereby a horizontally disposed open-ended rotatable drum may be provided with a bearing support at each end without the requirement of a shaft extending axially throughout.

Another object of the invention is to provide a novel bearing for the open end of a horizontally disposed rotatable drum which, when in its inoperative position, will provide free access to the interior of the drum, for the introduction and withdrawal of laundry.

Another object of the invention is to provide an improved closure means for a rotatable drum enclosing housing containing a washing solution which will support a rotatable bearing for the open end of a rotary drum when closed and provide free access to the interior of said drum for the introduction and withdrawal of laundry when in its opened position.

A further object of the invention is to provide a hinged closure means for the laundry introducing opening of a rotatable drum enclosing housing of a laundry machine which may be secured in fluid-tight sealing relation over the opening in a new and novel manner.

Other objects and advantages of the invention will be in part evident to those skilled in the art and in part pointed out hereinafter in connection with the accompanying drawing wherein there is shown by way of illustration and not of limitation, a preferred embodiment of the invention.

In the drawing:

Figure 1 is a fragmentary front view of a preferred form of closure means for a laundry machine constructed in accordance with the invention;

Figure 2 is a fragmentary view showing the door of Figure 1 as in its open position;

Figure 3 is a vertical sectional view taken through the center of a rotatable drum type laundry machine of the type contemplated by the present invention;

Figure 4 is a fragmentary view taken along line IV—IV of Figure 3, looking in direction of arrows;

Figure 5 is a fragmentary sectional view taken along line V—V of Figure 1, looking in direction of arrows, and;

Figure 6 is a fragmentary sectional view taken along line VI—VI of Figure 1, looking in direction of arrows.

2 While the present invention may find application in the small home laundry or washing machine art, its principal field of application will be found in connection with the production of the larger machines such as are used by commercial laundries, dry cleaning establishments and other industries where the washing or cleaning of larger batches of laundry require a relatively larger laundry accommodating drum. In the small family size washing machines the problem of supporting the laundry accommodating drum for rotation about a horizontal axis is not critical. This is explained by the fact that in these machines the rotating drums, while supported solely by a stub shaft or axle, are limited in size, being about one foot in depth and approximately two feet in diameter and have a capacity of approximately only twenty-five pounds of laundry. In the drawing, which accompanies this application, the invention is shown as applied to a large laundry or dry cleaning machine having a rotatable drum of a depth and diameter of approximately four feet and with a capacity of from two to four hundred pounds of laundry. With a machine of this larger size it will be readily seen that it would be impractical to support such a rotary drum upon a stub shaft in the manner employed with the aforementioned home type laundry machines, a good example of which is sold under the trade name of "Bendix." In these larger machines the employment of an axially extending shaft through the center of the drum with the bearings of both ends has the disadvantage that the laundry introducing and withdrawing opening in the end of the drum must be located at an off-center point. This, therefore, requires that the opening in the drum be brought into register with a corresponding opening in an outer enclosing housing all of which renders the introduction and removal of the laundry from the drum an extremely inconvenient operation. For example, if the laundry machine is stopped with the opening in its drum above the central axis the operator will have difficulty in reaching down into the drum to remove the contents thereof and if on the other hand the drum is stopped with its opening below its horizontal axis the withdrawal of laundry therefrom will be complicated by the fact that the laundry near the opening will be weighted down by other laundry above and thus also render the removal of the washed laundry difficult.

The more essential aspects of the present invention reside in the provision of a special form of closure means for an enclosing housing which, when closed, will provide a support for the ex-

tending or open end of a horizontally disposed rotatable drum which is mounted at its other end upon a stub shaft in the conventional manner with connections to a suitable driving unit by which the drum may be rotated at varying speeds. In practice the drum may be rotated at one speed during the washing operation and possibly another speed during a rinsing operation and finally at an extremely high speed for a drying operation, by which the contained rinse water is centrifugally removed.

Before describing the details of the invention reference is here made to Figure 3 of the drawing wherein the invention is shown as applied to a dry cleaning machine having a rotary drum 10 that is supported within an enclosing housing 11 and for rotation about a horizontal axis by a stub shaft 12. The stub shaft 12 is journaled in a bearing 13 and is adapted to be driven by an electric motor 14 through a multiple V-belt drive 15. The drum 10 is perforated and in this instance is shown as having four longitudinally extending ribs 16 which are disposed in equally spaced relation about its inner periphery and at its unsupported end the drum 10 also has a laundry introducing and withdrawing opening 17. In the present instance, the opening 17 is approximately twenty inches in diameter and arranged in axial relation with the opening 17 of the drum 10 there is a larger opening 18 in the enclosing housing 11. For closing this opening 18 in the housing 11 there is a door 19 that has an axially extending hub 20 which carries a drum supporting stub shaft for supporting the open end of the drum 10 as will hereinafter appear.

At this point it will be understood that the drum enclosing housing 11 is of water-tight construction and will be provided with suitable pipe connections by which water and/or a dry cleaning solution may be introduced and withdrawn therefrom in accordance with a timed cycle as is now employed in automatic washing machines. These pipe connections may also include a suitable solvent filtering system through which the cleaning solution can be passed for subsequent use after a cleaning operation. When employed in this manner and after the solution and/or water is withdrawn from the housing 11, the drum 10 is adapted to be rotated at a relatively higher speed as a preliminary drying operation and thus centrifugally remove any water remaining in the laundry within the drum.

As shown in Figures 1 and 2 of the drawings the closure 19 carried by the housing 11 is of disc-like configuration and is supported at one side by hinges 21. Arranged in spaced relation about the opening 18 and carried by the housing 11 there are three fixed bolt keepers 22 into which the ends of three bolts 23 carried by the closure member 19 extend. The bolts 23 are pivotally secured at their inner ends to a ring-like member 24 which is journaled for movement about the hub 20 which, as described above, is carried by the door or closure member 19. In this instance, the ring 24 is shown as provided with a radially extended lever arm 25 by which a turning movement may be imparted thereto. The bolts 23 are also shown as provided with an adjustable clevis 26 by which their effective length can be determined. These clevises 26 are in turn pivotally connected with bosses 27 carried by the ring 24. In this arrangement the bolts 23 are in a slightly off-radial or over-center position where a suitable stop associated with the ring 24 will serve to hold the bolts 23 in what may be termed an over-

toggle position when in their door locking positions as here shown. With this arrangement it will be seen that when the lever arm 25 is moved to the right or in a counterclockwise direction 5 as indicated by arrow, the three bolts 23 will be simultaneously moved from their over-toggle position and as the lever 25 is further operated to the right, these bolts will be withdrawn from their respective bolt keepers 22 after which the door 10 or closure member 19 will be released and free for opening. At this point it should be added that the outer ends of the bolts 23 are slidably mounted within a loosely fitting guide forming bosses 28 that are carried by the door 19.

15 While the shape and number of ribs 16 mounted within the rotatable drum 10 is not critical, I have in Figure 4 of the drawing shown the rib 16 as formed of sheet metal bent into channel configuration and secured at its outer edges to the interior of the drum by spot welding. With the ribs 16 constructed in this manner and their sides inclined at equal angles it will make little difference in which direction the drum 10 is rotated.

20 25 By now referring to Figure 5 of the drawing it will be noted that the opening 18 of the enclosing housing 11 is formed with an inwardly extending flange 29 into which an annular flange 30 carried by the closure member 19 is adapted to extend. The flanges 29 and 30 in this instance are of diameters which will provide a relatively firm fit. Outwardly beyond the flange 30 the closure member 19 also carries a sealing gasket 31 that will insure a water-tight seal in the housing 11 at this point. It will be also noted that the opening 17 in the end wall of the drum 10 is provided with an outwardly flaring flange 32 which provides a funnel-like opening into which a truncated conical head 33 carried by a stub

30 35 40 45 shaft 34 is adapted to tightly fit. The stub shaft 34 is journaled within the hub 20 by means of bearings 35 and at its outer end there is a thrust bearing 36 with an adjusting screw 37 by means of which it may be adjusted axially within the hub 20. In this manner it is possible to establish a firm contact between the funnel forming flange 32 upon the rotatable drum 10 and the truncated conical head 33 carried by the stub shaft 34 when the door or closure member 19 is

50 55 60 65 locked in its closed position by means of the bolts 23 as described in connection with Figure 1 of the drawing. In other words, when the truncated conical head 33 upon the stub shaft 34 is in engagement with the funnel-like flange 32 of the rotatable drum 10 it will in effect constitute the stub shaft 34 as a journaled axially extending support for the open end of the rotatable drum 10.

In Figure 6 of the drawing there is shown another detail of the invention which relates particularly to the closure securing means described above. In this latter figure of the drawing it will be noted that the bolts 23 are each provided with tapered or pointed ends 38 which are adapted to project into openings 39 carried by the bolt keepers 22. As here indicated the bolt receiving openings 39 are disposed inwardly in a slightly off-center position with respect to the normal axis of the bolts 23 so that when the bolts 23 are properly adjusted as to their length and secured by a lock nut 40 carried thereby the pointed ends 38 thereof will exert a wedging action which will operate to compress the sealing gasket 31 carried by the closure member 19 and thus insure a water-tight seal at the opening 18 in the housing 11. This will also insure a tight

fit between the drum engaging head 33 carried by the stub shaft 34 and the funnel forming flange 32 carried by the rotatable drum 10.

While I have, for the sake of clearness and in order to disclose the invention so that the same can be readily understood, described and illustrated a specific form and arrangement, it is to be understood that the invention is not limited to the specific form disclosed, but may be embodied in other forms that will suggest themselves to persons skilled in the art. It is believed that this invention is new and it is desired to claim it so that all such changes as come within the scope of the appended claim are to be considered as part of this invention.

Having thus described my invention, what I claim and desire to secure by Letters Patent is—

Apparatus for use in cleaning textiles, comprising: an enclosed liquid-tight housing adapted to contain a cleaning solution, said housing being formed at one end with a first circular opening having an inturned flange; a perforated drum adapted to contain textiles disposed within said housing for rotation about a horizontal axis, said drum being arranged coaxial with said opening and being formed at its end proximate said opening with a second circular opening having an angled outturned flange; a first bearing rigidly affixed to the end of said housing opposite said first circular opening; a first stub shaft affixed to the end of said drum opposite said second circular opening and disposed within said first bearing so as to rotatably support said drum, power means connected with said first stub shaft adapted to effect rotation of said drum relative to said housing; a circular door for closing said first opening; hinge means interconnecting said door and the exterior of said housing whereby said door may be swung towards and away from said first circular opening; a sealing gasket affixed to the periphery of said door; a hub coaxially affixed to said door; a second bearing disposed in said hub; a second stub shaft rotat-

ably and axially slidably mounted in said second bearing; a closure member for the outer end of said hub; an axially movable adjusting screw coaxially threadedly mounted by said closure member; a thrust bearing interposed between the outer end of said second stub shaft and the inner end of said adjusting screw whereby may be effected axial adjustment of said second stub shaft; a truncated conical head affixed to the inner end of said second stub shaft for closing said second circular opening when said door is moved into engagement with said first circular opening; a plurality of fixed bolt keepers mounted by the exterior of said housing in equidistantly-spaced relationship about said first circular opening; a ring coaxially rotatably mounted upon said hub adjacent the exterior of said door; a plurality of keeper-engaging bolts pivotally secured at their inner ends to said ring in position eccentric with respect to the radial disposition of said bolt keepers; and a radially extending lever secured at its inner end to said ring for turning said ring relative to said hub, said bolts being pointed at their outer ends and adjustable as to length whereby upon turning said ring their outer ends may be urged radially outwardly in unison into wedging relation with said bolt keepers so as to secure said door against said first circular opening with said sealing gasket in fluid-tight relationship thereto as said bolts approach a position in radial alignment with the axis of said hub and their respective bolt keepers.
